UNITED STATES PATENT OFFICE.

CASSIUS M. PARSON, OF KOKOMO, INDIANA.

WINDOW-SCREEN.

1,220,675.

Specification of Letters Patent. Patented Mar. 27, 1917.

Application filed December 1, 1916. Serial No. 134,398.

To all whom it may concern:

Be it known that I, CASSIUS M. PARSON, a citizen of the United States, residing at Kokomo, in the county of Howard and State 5 of Indiana, have invented certain new and useful Improvements in Window-Screens, of which the following is a specification.

My invention relates to an improvement in window screens, and more particularly to 10 that type of screen intended for use by having the wire fabric thereof mounted upon a spring roller with the loose end attached to the window sash so that as the sash is moved the screen will be extended from or 15 taken up by the spring roller.

An object of my invention is to provide a structure of the character as set forth which is of such form and construction that the parts may be embodied in conjunction with 20 the framing of a window as the window is being installed as new work, or the parts may be built into an old window.

Another object lies in providing a spring roller which is so formed that it partakes 25 substantially of the character of the usual shade roller, but has no means for catching to hold the roller against turning under the action of the spring, the parts being thus so arranged that as the window is either raised 30 or lowered in a sliding path the spring of the roller will permit ready extension of the screen or will take the same up properly.

Yet another object lies in providing means by which the roller is held against movement under the impulse of the spring during the installation in conjunction with a window, and in constructing means by which the roller will be removably held in place but 35 may be positively secured to be retained 40 against accidental or casual displacement.

With the above and other objects in view, my invention consists in certain novel features of construction and combinations of parts which will be hereinafter set forth in 45 connection with the drawings and then more particularly pointed out in the claims.

In the drawings:

Figure 1 is a view in elevation showing a window with my invention applied thereon. 50 Fig. 2 is a vertical sectional view taken on the line 2—2 of Fig. 1.

Fig. 3 is a view showing the spring roller and with the parts illustrated in section.

Fig. 4 is a fragmentary view taken on the 55 line 4—4 of Fig. 3.

Fig. 5 is a detail view in section taken on the line 5—5 of Fig. 3.

Fig. 6 is a detail view showing a modification which might be resorted to in the construction of the spring roller mounting.

The window frame which is formed to embody the side casing members 1 and 2 with the lintel 3 and sill 4 connected therewith is substantially of standard form and has the upper and lower sashes 5 and 6 mounted therein to be capable of sliding movement. To all intents and purposes, these parts are of usual construction, but in the roughing in of the framing around the window, clearance is to be left above the 60 lintel and below the sill. 65

The lintel is slotted through as shown at 7, adjacent to the outer edge of the upper sash, and the sill 4 has a similar slot 8 provided adjacent to the inner side of the lower sash. Roller supporting brackets 9 and 10 are mounted at the sides of the frame adjacent to the slotted openings 7 and 8, by being 70 secured on the side casing members 1 and 2 if desired, and these supporting brackets are 75 made of substantially the type now ordinarily used for shade rollers, the one being provided with a substantially circular orifice and the remaining bracket of each pair having a notch formed therein, after the manner 80 shown at 11 in Fig. 4. 85

Spring rollers 12 and 13 are mounted in these brackets 9 and 10 to extend across above the lintel 3 and below the sill 4, and to lie in parallelism with the openings 7 and 8. These spring rollers 12 and 13, which are substantially duplicates, comprise the wood, metal, or other cylindrical body portion 14 cored out or otherwise shaped at one end to provide the socket or opening 15. At the 90 opposite end of the body 14, a bearing pintle 16 is secured by being driven into the body, or in any other manner, this bearing pintle being of substantially cylindrical form so that it may be inserted in the circular opening of the one supporting bracket and will 95 turn freely therein. A block 17, which has a bearing provided therein for the spring mandrel 18 is shaped to be received in the bore or opening 15, and a pin 18 is provided 100 to hold this block against turning within the opening. A coil spring 19 is connected at one of its ends with a block 17 and after being wound around the mandrel 18 to substantially the outer end thereof is secured 105 110

through this mandrel by being passed through an opening therein, or in any other suitable manner. A plate 20 is provided over the open outer end of the bore 15, and thus the spring is housed entirely within this opening. The mandrel 18 is cut away on opposite sides as is indicated by the dotted lines in Fig. 4 and as shown by the full lines in Fig. 3, and thus a part is formed which 10 may be fitted into the notch 11 of the brackets 10. This fitting of the flat sided portion of the mandrel within the notch 11 will mount the mandrel to be held against turning movement with respect to the supporting bracket, and thus the spring 19 has 15 full control over the roller body. To secure the mandrel 18 against displacement from the notch 11, a substantially hooked shaped member 22 is carried on the supporting bracket 10 to be brought down over the mandrel after the same has been moved to 20 occupy a position at the bottom of the notch 11.

The rollers 12 and 13 have the wire mesh 25 or other screen strips 23 and 24 connected thereon and then wrapped around the rollers, and at their free ends these screen strips are connected with the upper and lower sashes respectively, it of course being understood 30 that the connection will be made with the top and bottom rails of these sashes. The screen strips are extended through the slots 7 and 8 previous to securement to the sashes and to insure that the fabric will not 35 pull out, reinforcing strips 25 may be placed over the connected edges as the screen strips are attached to the upper and lower sashes.

The parts can be assembled when the window is being built by mounting the supporting brackets 9 and 10 in the proper relations 40 before the frame is set in place, and then placing the rollers 12 and 13 in their proper positions before application of the interior trim, it of course being understood that the 45 sashes must be first fitted to work properly before the screen strips are brought through the slots 7 and 8 and are connected therewith. While the rollers 12 and 13 are being fitted in place, it will be desirable to maintain 50 the springs 19 in a partially wound condition, and as no catch means is provided, the parts as illustrated in Fig. 5 might be employed. As is here shown, the mandrel 18 is provided with a transversely extending bore 26 and a short length of wire 27 is inserted in this bore 26 and is then brought around and fastened in the opening 28 in the cover plate 20, this length of wire thus securing the mandrel against turning movement 55 under the impulse of the spring 19 after the mandrel has been turned to store up energy in the spring.

Where the screen structure is to be fitted to a window already built in, and even in 60 some instances where windows are being

newly placed, it may be awkward to apply the bracket portions 9 and 10 in the manner as above set forth, and therefore under these circumstances the supporting brackets can be formed after the manner shown in Fig. 6 70 with the supporting and attaching base thereof bent substantially at right angles to the main extent. The brackets 29 are then secured at the proper points upon a supporting base strip 30, which is made of comparatively narrow width and which may thus be inserted through a slot left or cut through the lintel and the sill. Following the insertion of the parts, the cut away portion can be inserted in place and then screws can be 80 used to secure the supporting base bar 30 in the proper mounting, it of course being understood that the screws will be passed through from the outer side of the lintel or sill to draw the base portion 30 tightly 85 thereagainst.

From the foregoing it will be seen that a screen structure is provided which disposes the screen portion in such relation that when the windows are closed, the screen strips are 90 entirely concealed, and as either sash is moved, the screen strip carried thereby is brought to cover over the opening as left by the shifting of the sash, that the parts as described may be fitted in conjunction with 95 a window as the same is built in or may be applied to windows already in place without material alteration and without destruction to the standing woodwork or trim of the window, and that the rollers as provided are 100 at all times positively maintained in the proper relation and operate to let out and take up the screen strips to insure that the same will be tightly stretched over the opening at all times while at the same time the 105 movement of the sashes will not be interfered with except in so far as the force of the spring is concerned; and, that the arrangement of the parts in the manner as set forth is such that when the sashes are 110 brought to the closed position, the screen strips will be rolled smoothly upon the rolls to thus be maintained against bulging or uneven stretching and will be protected from the weather.

The sash may have window lifts 31 secured thereon to aid in the raising and lowering, and if desired a strip 32, which may be of felt, rubber fabric, or other suitable material can be secured on one of the sash 115 to form a stop as the two sash are brought to intermediate position, it being preferable that this strip be secured on the lower side of the bottom rail of the upper sash as in this mounting the strips 32 will exclude flies 120 or other insects from finding their way up between the two sashes. It will of course be understood that the screen strips 23 and 24 are to fit over at their edges rather snugly 125 against the side casing portions 1 and 2, and 130

thus flies and other insects will be excluded at these points.

While in the foregoing I have shown and described only specific forms of construction, it will be understood that this structure might be adapted for use in hospitals and in other places by having fabric inserted in place of the screen strips to thus permit passage of air but to cut off strong currents of air or draft, and that a number of other changes and modifications might be resorted to in the form and arrangement of the several parts as in the manner of application, without departing from the spirit and scope of my invention and in view of this fact I do not wish to be limited to the exact disclosure but only to such points as may be set forth in the claims.

I claim:

1. Window screen means including in combination with a window of the check-rail type, a roller mounted above the lintel, a second roller mounted below the sill of the window, said lintel and sill being provided 25 with slots formed adjacent the outer side of the upper and lower sashes respectively, screen strips mounted upon said rollers and connected at their free ends with the top and bottom rails of the lower and upper 30 sashes respectively, and a strip mounted upon the lower rail of the upper sash to provide a stop against the passage of insects between the sashes.

2. A window screen adapted for application to a window having a sliding sash including a base strip to be mounted on the casing of the window and having supporting brackets carried at the ends thereof, a spring roller mounted upon said supporting 40 brackets, and a screen strip connected at one of the ends with the roller adapted to be attached at its free end to the window and to thus be mounted in the position for use when the base strip is secured to the casing.

3. A window screen comprising in combination with a sash mounted to be capable of sliding movement to an open relation, a screen strip connected at one of its ends to that edge of the sash which moves forward

to leave the opening, a roller provided with an opening at one end and having a bearing pintle at the opposite end, a spring mandrel mounted in the open end of said roller, a spring mounted about said mandrel connected at one of its ends with the mandrel and at its opposite end with the roller, said mandrel provided with a flat portion, supporting brackets mounted in conjunction with the casing of the window to receive the bearing pintle and the flat portion of the 60 spring mandrel, the screen strip being connected at its free end with the roller, and means to secure the spring mandrel against displacement from the bracket in which the same is fitted. 65

4. A window screen comprising in combination with a sash mounted to be capable of sliding movement to an open relation, a screen strip connected at one of its ends to that edge of the sash which moves forward 70 to leave the opening, a roller provided with an opening at one end and having a bearing pintle at the opposite end, a spring mandrel mounted in the open end of said roller, a spring mounted about said mandrel connected at one of its ends with the mandrel and at its opposite end with the roller, said mandrel provided with a flat portion, supporting brackets mounted in conjunction with the casing of the window 75 to receive the bearing pintle and the flat portion of the spring mandrel, the screen strip being connected at its free end with the roller, means to secure the spring mandrel against displacement from the bracket in 80 which the same is fitted, and means to secure the spring mandrel against turning movement when the same has been wound to tighten the spring and store up energy 85 therein so that the rollers can be fitted in the proper mounting. 90

In testimony whereof I affix my signature in presence of two witnesses.
